John P. Young, Bronxville, N.Y., and Charles A. Arnold, Providence, R.I., assignors to Lyon Incorporated, Detroit, Mich., a corporation of Delaware

Application April 22, 1958, Serial No. 50,580

Term of patent 14 years

(Cl. D54—12)

Fig. 1 Fig. 2

The essential features of our design reside in the handle portion shown in full lines on the drawing.

The appearance of the opposite face and edge of the handle not shown are identical with the face and edge as shown herein in Figures 1 and 2.

We claim:

The ornamental design for a knife or similar article of flatware, substantially as shown and described.
